LEVER MOUNTED DOUBLE PAWL ALTERNATELY GRIPPING RING AND SUN GEAR

Wallace D. Ellison, West Los Angeles, Calif.

Application September 6, 1949, Serial No. 114,086

5 Claims. (Cl. 74—143)

1

This invention comprises novel and useful improvements in a double ratchet and more specifically pertains to a ratchet handle for tools such as socket wrenches, brace and bits and the like.

The primary object of this invention is to provide an improved ratchet handle for tools which is capable of imparting a continuous step by step rotation to a tool upon oscillation of the handle of the device and at an equal or amplified speed of rotation of the tool holder relative to the speed of oscillation of the handle.

A further object of the invention is to provide a ratchet handle in conformity with the foregoing object in which the handle may be selectively locked to the tool carrying element for employment as a rigid wrench assembly.

A still further object of the invention is to provide an improved reversible ratchet mechanism for selectively operating the tool carrying element of the device in either direction of rotation upon oscillation of the handle of the device.

Yet another important object of the invention is to provide a ratchet mechanism which shall be of simple and inexpensive construction, shall have an improved ratchet adjusting and ratchet operating mechanism, and which shall be readily assembled or disassembled as desired.

These, together with various ancillary features and objects of the invention which will later become apparent as the following description proceeds, are attained by the present device, a preferred embodiment of which has been illustrated by way of example only in the accompanying drawings, wherein:

Figure 1 is a top plan view of one embodiment of the invention;

Figure 2 is a horizontal sectional view of the embodiment of Figure 1 taken substantially upon the plane of the broken section line 2—2 of Figure 3;

Figure 3 is a vertical longitudinal sectional view through the embodiment of Figure 1, taken substantially on the plane of the broken section line 3—3 of Figure 1;

Figure 4 is an enlarged detail view in vertical section through a portion of the device showing certain details of the ratchet mechanism of the same; and

Figure 5 is a fragmentary view in bottom plan showing the ratchet mechanism in one of its operative positions, being taken substantially upon the broken section line 5—5 of Figure 4.

Referring now more specifically to the accompanying drawings, wherein like numerals designate similar parts throughout the various views, it will be seen that the ratchet handle forming the subject of this invention comprises a pair of handles 10 and 12 which at one end are flat-

2

tened and laterally enlarged and are provided with complementary cup-shaped portions 14 and 16 respectively which are adapted to register with each other and form between the same an annular chamber containing the operating parts of the ratchet assembly.

A hub 18 having a longitudinal bore 20 extending therethrough to comprise a socket for detachably receiving the shank of a tool of any desired character, extends through suitable apertures in the top and bottom walls of the cup members 14 and 16, and is provided with annular grooves 22 and 24 upon the opposite extremities of the hub portion for receiving detachable split rings 26, which thus abut the exterior surfaces of the walls of the cup members 14 and 16.

It will thus be seen that the cup members serve to journal the hub or socket member therebetween, while the latter serves to retain the cup members in registration with each other and constitutes a pivot about which the two handles 10 and 12 may be oscillated.

Obviously, it is merely necessary to remove one or both of the split rings 26 in order to readily disassemble the device to inspect the interior of the ratchet casing as desired.

At its central portion, the hub member 18 is diametrically enlarged to form a sun gear 28, and this gear may be integrally formed upon the hub or may be separately formed and rigidly and mechanically attached thereto in any desired manner.

Loosely and rotatably received in the interior annular walls of the cup members 14 and 16, is a ring or orbit gear 30 which as shown in Figure 3 substantially covers the entire cylindrical inner surface of the registering cup members which thus constitute journals for the orbit gear. Freely rotatable upon an axle 32 which is received within the chamber of the cup members and carried by the member 14 is a planet gear 34 which meshes with both the orbit gear and the sun gear for transmitting relative movement therebetween.

As will now be better seen from Figure 4, the other cup member 16 has journaled therein a ratchet pivot pin 36 which has rigidly secured to its exterior portion an actuating lever 38 having a detent portion 40 thereon. This pin 36 extends throughout substantially the entire height of the ratchet chamber within the mating cups, and by oscillation of the lever 38 from the full to dotted line position shown in Figure 1 may be given an oscillatory motion in order to adjust the ratchet mechanism.

A knob or projection 42, see Figure 1, extends above the surface of the cup 16 for engagement by the detent 40, and it is contemplated that there should be sufficient resiliency in the detent

40 or in the lever 38 to permit the same to yield and be forced past the projection 42, which thus serves as a yieldable stop for maintaining the lever and the ratchet in adjusted position.

The ratchet mechanism further includes a pair of wings 44 and 46 which at their outer end terminate in oppositely extending jaws 48 and 50 for the wing member 46 and 52 and 54 for the wing member 44. These jaws are of such shape that they may be alternately engaged with the teeth of the orbit and sun gears as will be apparent from the position shown in Figures 2 and 5.

At their adjacent ends, the jaws are pivotally connected to the ratchet pivot pin 36, as by means of a tongue portion 56 extending centrally from the end of the jaw 44 for journaling upon the pin 36, and by bifurcated portions 58 which likewise are pivoted to the pin 36 and embrace the extension 56. The jaws are thus free to individually pivot about the pivot pin within the space between the orbit and sun gears.

Upon their bottom surfaces, that is the surfaces adjacent the cup 14, the pivot ends of the jaws 44 and 46 are provided with recesses 60 forming seats for receiving the extremities of a flexible leaf spring 62 which extends through a diametrical slot extending inwardly from the end of the pivot pin 36. A cotter pin 64 disposed through aligned bores in the spring and pivot pin serves to detachably secure the spring upon the pin and the latter within the cup members 14 and 16. This leaf spring thus serves to force the wing members against the orbit gear 30 and the sun gear 28 depending upon which way the lever 38 is turned.

From the foregoing, the construction of the device will now be understood and the operation of the same is as follows. Upon oscillation of the handles 12 with respect to 10, the hub or socket member 29 will be rotated step by step in the same direction, this direction depending upon the setting of the ratchet member. Considering that one of the handles 10 is held stationary, oscillatory movement of the other handle 12 in one direction will cause rotation of the planet gear upon the orbit gear and thereby will cause rotation of the sun gear in its journal in the two cup members but with the movement of handle 12 in the opposite direction, planet and orbit gears idle while the handle locks directly to the sun gear. This imparts amplified rate of movement to the sun gear by virtue of the difference in diameters of the sun and orbit gears. In one direction of movement of the handle 12 with respect to the handle 10, the ratchet member will slip over the sun gear while being locked to the orbit gear which will turn the planet gear, which in turn will rotate the sun gear in the direction stated above, and upon the reverse movement of the handle 12 with respect to handle 10 the same will lock the jaw 46 and sun gears together thereby positively rotating the sun gear. Upon reversal of the position of the ratchet by moving the lever 38 to the other side of the projection 42, the jaws will reverse their engagement with the gears thus effecting rotation of the sun gear in the same manner but in a reverse direction. However, when the two handle members 10 and 12 are held together the entire device operates as a conventional ratchet wrench and may be employed as such.

Obviously, the device could be used to operate socket wrenches, by detachably securing the shanks of the same within the bore 20; but the

device can also be used in the same manner as a ratchet brace and bit or the like.

From the foregoing, the construction and operation of the device will be readily understood and further explanation is believed to be unnecessary. However, since numerous modifications and changes will readily occur to those skilled in the art after a consideration of the foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. A ratchet handle for tools comprising a pair of handles terminating in complementary mating cups forming an annular chamber, an orbit gear free to rotate in both cups, a sun gear having a hub extending through and journaled in each cup, said hub having a socket for receiving a tool shank, an axle carried by one cup, a planet gear journaled on said axle and meshing with said orbit and sun gears, a ratchet operatively connected with said sun and orbit gears for locking a handle to one of said sun and orbit gears, said ratchet having a pivot pin carried by the other cup and extending through the same.
2. A ratchet handle for tools comprising a pair of handles terminating in complementary mating cups forming an annular chamber, an orbit gear free to rotate in both cups, a sun gear having a hub extending through and journaled in each cup, said hub having a socket for receiving a tool shank, an axle carried by one cup, a planet gear journaled on said axle and meshing with said orbit and sun gears, a ratchet operatively connected with said sun and orbit gears for locking a handle to one of said sun and orbit gears, said ratchet having a pivot pin carried by the other cup and extending through the same, said ratchet comprising a pair of oppositely extending wings, each wing terminating in oppositely extending dogs alternately engageable with the sun and orbit gears.
3. The combination of claim 2 wherein said wings are pivoted to said pin.

4. The combination of claim 2 including a resilient key fixed to said pin, said key engaging seats in said wings for yielding biasing said dogs into operative engagement with one of said gears upon rotation of said pin.

5. The combination of claim 2 including an actuating lever on said pin, a projection on said other cup, said lever yielding engaging said projection for maintaining said ratchet in selected operating position.

WALLACE D. ELLISON.
